GEORGE G. GOING, OF GLENBROOK, CONNECTICUT, ASSIGNEE TO REMINGTON TYPE-
WRITER COMPANY, OF ILION, NEW YORK, A CORPORATION OF NEW YORK

TYPEWRITING MACHINE

Application filed January 20, 1930. Serial No. 422,077.

My invention relates to typewriting and like machines and more particularly to the type actions thereof.

The main object of my invention, generally stated, is to provide extremely simple and effective means for controlling the movements of pivoted type bars so as to produce substantially noiseless pressure imprints.

A further object of the invention is to attain these ends without interfering with the visibility of the writing produced on the machine.

A still further object of the invention is to provide means of the character specified which may be employed in standard typewriting machines without materially modifying the existing structural features thereof.

To the above and other ends which will hereinafter appear my invention consists in the features of construction, arrangements of parts and combination of devices set forth in the following description and particularly pointed out in the appended claims.

In the accompanying drawings wherein like reference characters indicate corresponding parts in the different views—

Fig. 1 is a fragmentary, detail, central, vertical, fore and aft, skeletonized sectional view of a machine embodying my invention, only so much of the machine being shown as is necessary to illustrate my invention in its embodiment therein.

Fig. 2 is a detail, fragmentary front view of some of the parts.

Fig. 3 is an enlarged, detail, fragmentary, vertical sectional view taken through the pivotal axis of the momentum accumulator.

Fig. 4 shows in perspective and detached, the type bar center guide and the parts carried thereby.

The present invention is in the nature of an improvement on the construction disclosed in my Patent No. 1,615,694, dated Jan. 25, 1927.

The type actions represented are conventional ones, except for slight modifications of each type bar, as will presently appear.

As shown each key lever 1 is pivoted at 2 and provided with a finger key 3. There is, or may be, the usual full complement of forty-
two key levers, each controlling a separate

type bar. Thus, each key lever is connected at 4 to one arm of a sub-lever 5 mounted to turn on a fixed pivot wire 6 carried by a slotted supporting bar 7. The upright arm of each sub-lever carries a pin 8 that works in a cam slot 9 in the heel of the associated type bar 10, said arms being progressively longer as the sides of the system of type bars are approached.

The segmentally arranged type bars are pivoted on a pivot wire 11 carried by a slotted type bar segment 12, each type bar working in a separate radially disposed slot 13 in the segment and carrying two types 10^a and 10^b. The free ends of the type bars are normally supported on a padded type bar rest or support 14. The type bars are bent laterally at their type-carrying ends at 15, the angularity of the bent portions relatively to the bars increasing as the sides of the system are approached, as usually provided in order that each type block 10^c may be disposed in the same fore and aft vertical plane when in the printing position, and as indicated in dotted lines in Fig. 2.

From Fig. 2 it will be seen that, as is usual in such constructions, the planes of movement of all of the type bars, intermediate their pivots and the bends therein, converge below the printing line, said point of convergence corresponding to the line 15 of the bend in each type bar when in printing position.

In the present instance I provide the usual type bar center guide, indicated as a whole by the reference numeral 16 and which is secured by screws 16^a to the type bar segment. This type guide has guiding jaws 17 with which a contact portion 18 on each type bar coacts to direct the bar to printing position in the usual manner.

I provide a single controlling member or momentum accumulator, indicated as a whole by the reference numeral 19 and shown detached in Fig. 4. This member 19 is located in front of the platen 20 below the printing line and extends in the path of and is actuated by and controls each type bar as it approaches the printing position, to effect a slowing down of the actuated bar and

exert the stored energy of said member 19 on the bar to effect substantially a noiseless pressure imprint. I prefer to pivot the member 19 below the printing line on the type bar center guide and to so construct, arrange and mount said member 19 that it will not obstruct the operator's view of the printing line or the writing.

As shown more clearly in Fig. 4 the momentum accumulator or controlling member 19 comprises, in the present instance, two parallel side arms or members 21 shaped alike and fixedly united and maintained spaced apart by connecting rods 22 and 23. The distance that these members 21 are spaced apart corresponds substantially to the width of the upright supporting arm of the type bar center guide 16, so that a member 21 may be located on each side of the center guide and swing relatively thereto. Each of the members 21 is pierced intermediate its ends at 24 to receive a pivot for pivotal support on the center guide 16.

In the present instance one of the members 21 is pivoted on a shouldered pivot screw 25 (Fig. 3) received at its threaded end in a tapped opening 26 in one side of the type guide. The other member 21 receives a pivotal support on a sleeve 27 provided with hexagonal head 28. The stem of a headed supporting and binding screw 29 passes through the sleeve 27 and is received at its threaded end in a tapped opening 30 in the center guide 16.

35 A very light returning spring 31 is coiled around the sleeve 27 and is anchored at one end in an opening 32 in the head 28 of said sleeve. The other end of the spring is secured in a hole 33 in one of the members 21. 40 The force of the light spring 31 is exerted to return the controlling member 19 to normal position and is sufficient only to attain this result, and without materially affecting the actuating movement of said member in conjunction with a type bar. The parts 27-28 and 29 not only constitute means co-acting with one of the members 21 for pivotally mounting the controlling member 19, but also constitute adjustable means whereby 50 the effective force of the spring 31 on said member may be varied. Thus, by backing up the screw 29 clamping pressure on the sleeve 27 is released and said sleeve with the aid of its head 28 may be turned in one direction or 55 the other to increase or decrease the effective force of the spring 31, as may be desired. The screw 29 may then be tightened to hold the sleeve in the rotative position to which it has been adjusted.

60 The lower end portion 34 of each member 21 constitutes a weighted part that may swing past the type bar segment through a segmental cut-out 12* therein. The cross rod 22 on the member 19 constitutes a contact 65 with which each type bar coats in its ap-

proach to the printing position to set the momentum accumulator 19 in motion. When the member 19 is in the normal dotted-line position shown in Fig. 1, the contact 22 is maintained in the path of a cam slot 35 in each type bar of a width corresponding substantially to the diameter of the contact. As a type bar reaches the dotted-line position in Fig. 1, the contact 22 will first coat with the bottom wall 36 of the cam slot and the continued motion of the bar will cause the member 19 to be turned by a camming action thereon to the full line position. When the contact 22 enters the cam slot in a type bar there is established an interlocking connection between the controlling member and type bar. The effect therefore, when a type bar reaches the controlling member is that said type bar is slowed down in the act of picking up and actuating said member. Due to the interlocking connection between the two the stored energy in the controlling member or momentum accumulator will be exerted on the connected type bar at the last part of its printing stroke and a substantially noiseless pressure imprint will be effected. It will be seen that this pressure by the member 19 is exerted on each type bar between the bend 15 therein and the outer free end of the bar and near the types thereon in the direction of the axis of the platen, and where pressure on a pivoted type bar is most efficaciously applied. This is especially true when bent type bars are employed, since to apply pressure intermediate the bend in each type bar and its pivot tends to effect a cranking or off-set force on the bar and throw the type "off their feet" when such pressure is applied after the type bar reaches the platen. The present construction overcomes this difficulty and applies pressure from the member 19 near the type-carrying end of the type bar where such pressure is most effective, without, nevertheless, interfering with the operator's line of vision of the printing line.

100 The movement of each type bar under control of its key is unrestrained until it reaches the dotted-line Fig. 1 position when it picks up the member 19 and after it has acquired its highest speed. Therefore no resistance due to the operation of the member 19 is felt by the operator on the finger key, since ordinarily, the finger key will have been released by the operator by the time the type bar reaches the dotted-line position.

105 In order that the member 19 may normally be held in position where its contact 22 will enter the cam slot 35 on any actuated type bar, I have provided means for arresting the member 19 in its return to normal position. Any suitable means may be employed for this purpose. In the present instance I provide a stop bar 37 secured to and extending beyond the sides of the type bar center guide 16 in the path of return movement of the 110

member 19, and where the edges 38 thereof will coat with the projecting ends of the bar 37 to effect an arrest of the member 19 under the reaction of its spring 31.

5 In order to reduce or prevent any appreciable noise by the member 19 being arrested in its return movement by its stop 37 I provide suitable sound deadening features. Such features in the present instance comprise a 10 very light leaf spring 39 secured at its center to the type bar guide 16 between the latter and the stop bar 37. The free ends of this spring extend in front of and normally project forward from and out of contact with 15 the projecting ends of the stop bar 37. The free end portions of this spring project into the path of the edges 38 of the member 19, and as the latter returns to normal position will compress the spring against the stop bar 20 37 and arrest the member 19 with little or no noise. It should be understood that the thickness of the spring 39 is exaggerated in the drawings and that in practice it is very light and is insufficient to overcome the effective 25 force of the spring 31, which also is a very light spring.

From the foregoing description it will be understood that I have provided simple and effective means, which may be readily employed in standard typewriting machines without materially changing the existing structural features thereof, for slowing down the movement of each type bar as it approaches the printing point and effecting substantially a noiseless pressure imprint.

Various changes may be made in the construction, and parts thereof may be employed without others, without departing from my invention as it is defined in the accompanying claims.

40 What I claim as new and desire to secure by Letters Patent is:

1. The combination of a platen, a series of pivoted type bars, key controlled means for actuating each type bar, and means for slowing down the movement of each type bar as it approaches the printing point and effecting substantially a noiseless pressure imprint, said means comprising a single momentum 45 accumulator arranged below the printing point and in the path of the type-carrying end portion of each type bar to be actuated thereby, and means by which the energy of the momentum accumulator thus actuated is exerted on the actuated type bar at the last part of its printing movement to effect substantially a noiseless pressure imprint against the platen or the paper thereon.

2. The combination of a platen, a series of 50 pivoted type bars, key controlled means for actuating each type bar, and means for slowing down the movement of each type bar as it approaches the printing point and effecting substantially a noiseless pressure imprint, said means comprising a single momentum ac-

cumulator arranged below the printing point and in the path of the type-carrying end portion of each type bar to be actuated thereby, and means by which an interlocking connection between each type bar and said momentum accumulator is automatically effected so that the energy of the latter is exerted on the type-carrying end portion of the actuated type bar to effect a pressure imprint against the platen or the paper thereon.

3. The combination of a platen, a series of pivoted type bars, key controlled means for actuating each type bar, and means for slowing down the movement of each type bar as it approaches the printing point and effecting substantially a noiseless pressure imprint, said means comprising a single momentum accumulator arranged in the path of the type-carrying end portion of each type bar to be actuated thereby, and means by which the energy of the momentum accumulator thus actuated is exerted on the actuated type bar at the last part of its printing movement to effect substantially a noiseless pressure imprint against the platen or the paper thereon, said last mentioned means comprising a pin and slot connection between each actuated type bar and the momentum accumulator brought into effective engagement as such type bar approaches the printing position.

4. The combination of a platen, a series of pivoted type bars, key controlled means for actuating each type bar, and means for slowing down the movement of each type bar as it approaches the printing point and effecting substantially a noiseless pressure imprint, said means comprising a single momentum accumulator arranged in the path of each type bar to be actuated thereby, an engaging portion carried by said momentum accumulator, and each type bar having a slot in which said engaging portion is received as an actuated type bar approaches the printing position, whereby the energy of the momentum accumulator is exerted on the actuated type bar to effect substantially a noiseless imprint.

5. The combination of a platen, a series of pivoted type bars each having a slotted cam therein, key controlled means for actuating each type bar, and means for slowing down the movement of each type bar as it approaches the printing point and effecting substantially a noiseless pressure imprint, said means comprising a single momentum accumulator arranged in the path of each type bar to be actuated thereby, and an engaging pin carried by said momentum accumulator and which is received in said cam slot in an actuated type bar as the latter approaches the printing position, whereby said momentum accumulator may be gradually set in motion by a type bar and an interlocking connection between the actuated type bar and the momentum accumulator is effected and

the stored energy of the latter is transmitted to the connected type bar.

6. The combination of a series of pivoted type bars, a cam on each type bar, key controlled means for actuating each type bar, and means for slowing down the movement of each type bar as it approaches the printing point and effecting substantially a noiseless pressure imprint, said means comprising a single momentum accumulator arranged in the path of each type bar to be actuated thereby, and a contact member carried by said momentum accumulator and with which the said cam on each type bar coacts as the latter approaches the printing position, whereby the momentum accumulator may be actuated by a type bar with a camming action.

7. The combination of a platen, a series of pivoted type bars, key controlled means for actuating each type bar, and means for slowing down the movement of each type bar as it approaches the printing point and effecting substantially a noiseless pressure imprint, said means comprising a single momentum accumulator mounted to turn on a fixed pivot below the printing point and in the path of each type bar to be actuated thereby and having a contact member with which an engaging portion on each type bar intermediate the ends thereof coacts, the stored energy of the actuated momentum accumulator being exerted on the actuated type bar at the last part of its printing stroke.

8. The combination of a platen, a series of pivoted type bars, key controlled means for actuating each type bar, and means for slowing down the movement of each type bar as it approaches the printing point and effecting substantially a noiseless pressure imprint, said means comprising a single momentum accumulator pivoted intermediate its ends on a fixed portion of the machine below the printing point and having at its upper end a contact member with which a portion of each type bar intermediate its ends coacts as the actuated type bar approaches the printing position, said momentum accumulator having a weighted portion at its lower end.

9. The combination of a platen, a series of pivoted type bars, key controlled means for actuating each type bar, and means for slowing down the movement of each type bar as it approaches the printing point and effecting substantially a noiseless pressure imprint, said means comprising a single momentum accumulator having two united parallel side arms pivoted intermediate their ends to turn on a fixed support and having a contact pin between said arms and with which each of the type bars coacts in its movement to printing position.

10. The combination of a platen, a series of pivoted type bars, key controlled means for actuating each type bar, and means for slowing down the movement of each type bar as it

approaches the printing point and effecting substantially a noiseless pressure imprint, said means comprising a single momentum accumulator having two united parallel side arms pivoted intermediate their ends to turn on a fixed support and having a contact pin between said arms, each type bar having a cam slot in which said contact pin is received as a type bar approaches the printing position.

11. The combination of a series of pivoted type bars each having a cam slot therein, and a single momentum accumulator in the path of all of said type bars and actuated by each of them, said momentum accumulator having an engaging portion received in the cam slot in any of said type bars as it approaches the printing position, whereby the momentum accumulator may be actuated by any type bar with a camming action and the stored energy of the momentum accumulator will be exerted on the actuated type bar at the last part of its printing stroke to effect a substantially noiseless pressure imprint.

12. The combination of a series of pivoted type bars, a momentum accumulator in the path of and actuated by each of said type bars and exerting its stored energy on each type bar to effect substantially a noiseless pressure imprint, said momentum accumulator consisting of a single member pivoted below the printing point and normally disconnected from the type bars, and means for bringing each type bar at the last portion of its printing movement into interlocking working engagement with said momentum accumulator and the latter exerting its stored energy on the type bar near its type-carrying end thereof.

13. The combination of a platen, a series of type bars that are provided with lateral bends where they converge at a single point below the print line, a single momentum accumulator arranged in front of the platen and in the path of said type bars and by which each type bar is applied with a substantially noiseless pressure imprint, means on each type bar intermediate the bend therein and the free end thereof for engaging and actuating the momentum accumulator and causing it to exert its stored energy on the engaged type bar.

14. The combination of a series of type bars that are provided with lateral bends where they converge at a single point below the print line, a single momentum accumulator arranged in front of the platen and in the path of said type bars and by which each type bar is applied with a substantially noiseless pressure imprint, and a slotted cam on each type bar intermediate the bend therein and the free end thereof for interlocking with and engaging and actuating the momentum accumulator and causing it to exert its

stored energy on the engaged type bar at the last portion only of its printing stroke.

15. The combination of a series of type bars that are provided with lateral bends where they converge at a single point below the print line, a center guide for the type bars which coacts with each of them intermediate the bend therein and the free end of the bar, a single momentum accumulator pivoted on 5 said type guide and arranged in the path of the type bars to be actuated thereby, and means on each type bar intermediate the bend therein and the free end of the bar for effecting an interlocking actuating engagement 10 with said momentum accumulator, whereby the latter is effective at the last portion of the printing movement of each type bar to slow down its movement and cause the stored energy of the momentum accumulator to be 15 exerted on the engaged type bar near the type-carrying end thereof and effect substantially a noiseless pressure imprint.

16. The combination of a series of pivoted type bars each having a slotted cam therein, 20 key controlled means for actuating each type bar, and means for slowing down the movement of each type bar as it approaches the printing point and effecting substantially a noiseless pressure imprint, said means comprising a single momentum accumulator arranged in the path of each type bar to be actuated thereby, an engaging pin carried by 25 said momentum accumulator and which is received in said cam slot in each actuated type bar as the latter approaches the printing position, whereby said momentum accumulator may be set in motion by a type bar with a camming action and an interlocking connection between the actuated type bar and the 30 momentum accumulator is effected and the stored energy of the latter is transmitted to the connected type bar, arresting means for 35 limiting the return movement of the momentum accumulator to normal position ready to 40 coact with said slotted cam on each type bar, and a spring for returning said momentum 45 accumulator to normal position.

17. The combination of a platen, a series of pivoted type bars each having a slotted cam therein, key controlled means for actuating each type bar, and means for slowing down the movement of each type bar as it approaches the printing point and effecting substantially a noiseless pressure imprint, said means comprising a single momentum accumulator arranged in the path of each type bar to be actuated thereby, an engaging pin carried by said momentum accumulator and which is received in said cam 55 slot in an actuated type bar as the latter approaches the printing position, whereby said momentum accumulator may be set in motion by a type bar with a camming action and an interlocking connection between the 60 actuated type bar and the momentum ac-

cumulator is effected and the stored energy of the latter is transmitted to the connected type bar, arresting means for limiting the return movement of the momentum accumulator to normal position ready to coact with said slotted cam on each type bar, a spring for returning said momentum accumulator to normal position, and adjustable means for varying the effective force of said spring.

Signed at Stamford, in the county of Fairfield and State of Connecticut, this 18th day of January, A. D. 1930.
